ABSTRACT

A carrying handle for cardboard cartons having two sets of opposed overlapping top flaps, including a base plate with four threaded studs equiangularly positioned on the base plate so that with the base plate appropriately positioned beneath the closed flaps each threaded fastener extends through aligned openings in two of the flaps, there being provided a top plate over the closed flaps with four apertures for receiving the threaded studs, with wing nuts on the studs for holding the plates together, and a carrying handle fixed to the top plate.

CARRYING HANDLE ASSEMBLY FOR CARTONS

BACKGROUND OF THE INVENTION

The manual lifting of cardboard containers of relatively large size has been a significant problem with salesmen, displayers, and others who transport the same carton between different locations. The transporting of cartons of a large size by supporting them on the shoulder is not only quite difficult, but a maneuver which is not facilitated by conventional clothing as worn by salesmen and other white-collar workers.

One solution for carrying cartons in the past is to wrap the entire carton in string and attach a removable handle to the string portions at the top of the carton. This solution has not proved entirely satisfactory because the handle assembly tends to pull over too far to one side of the carton, particularly if the article within the carton has a considerable weight.

It is a primary object of the present invention to minimize the problems noted above with the prior art.

SUMMARY OF THE PRESENT INVENTION

In accordance with the present invention, a carrying handle assembly is provided that releasably attaches to the top flaps of a cardboard carton and permits the carton, even though it be of considerable size, to be easily carried from one location to another by the carrying handle.

Cardboard cartons are generally constructed so that they have four overlapping top flaps, with opposed flaps in nearly abutting relation. Basically, there are provided top and bottom plates between which these carton flaps are sandwiched to provide an excellent grip on the carton.

Toward this end, the bottom plate is provided with four equiangularly spaced upwardly projecting studs with the studs being positioned so that each extends through two adjacent top flaps of the carton. In this manner, the studs extend through the grip in toto eight openings in the top flaps, two in each flap.

A top plate rests on top of the flaps and has four openings which receive the upwardly projecting studs. Wing nuts threadably engaging the studs rigidly clamp the flaps between the two plates. A handle is provided fixed to the top plate for manual carrying of the entire box or container.

The method of fixing the present carrying handle apparatus to the container also forms a part of the present invention. In order to accurately make the receiving holes in the flaps in the proper position, the flaps are closed, and the bottom plate placed upside down on top of the flaps and the flaps marked by a pencil or pen at the location of the studs. The top plate is then removed and the pencil marks are punched through all four flaps of the carton.

The bottom plate is then turned with the studs facing upwardly and placed within the container held in place either by the article within the container or by a piece of cardboard cut the size of the inside of the container so that it fits snugly therein and supports the bottom plate near the top of the container to facilitate placement of the flaps in the closed position with the cover plate inside the container. Thereafter, one opposed set of flaps is closed over the bottom plate with the studs projecting through each flap and thereafter the opposite opposed set of flaps are closed over the same studs.

The top plate is then placed over the projecting studs and the wing nuts fastened into position.

It should be understood that the present handle is readily removable and may be used over and over again on different containers as desired.

BRIEF DESCRIPTION OF THE DRAWINGS

FIG. 1 is a perspective view of a container with the carrying handle assembly according to the present invention shown in its affixed position;

FIG. 2 is a cross section taken generally along line 2-2 of FIG. 1 illustrating the carrying handle assembly and its relationship to the container flaps; and

FIG. 3 is an exploded view of a container and the carrying handle assembly according to the present invention.

DETAILED DESCRIPTION OF THE PREFERRED EMBODIMENT

Referring to the drawings and particularly to FIGS. 1 and 2, a carton 10 of conventional construction is illustrated having a carrying handle assembly 12 in its affixed position as shown in FIG. 1. Handle assembly 12 is particularly useful for manually carrying cartons 10 of considerable size and weight from one location to another.

The container 10 is seen to include side walls 15 and 16 that have projecting from the upper ends thereof flaps 17, 18, 19 and 20. The flaps 17 and 19 are referred herein to as opposed flaps as are the flaps 18 and 20, and when these opposed flaps are in their closed position, their ends are spaced somewhat as shown at 22 in FIG. 2.

The handle assembly consists of a bottom plate 24, top plate 25 and a handle 26 rivited as at 27 to the top plate 25.

The bottom plate 24 is rectangular in construction and has rigidly fixed thereto four upwardly projecting threaded studs 28, 29, 30 and 31. The studs are positioned at the corners of an imaginary square on the plate 24 and are also equiangularly spaced on the plate.

The bottom plate 24 lies immediately below the lowermost flaps 17 and 19 centrally of the container as shown in FIG. 2, Stud 28 projects through openings 36 in flap 17 and 37 in flap 20. Stud 29 projects through openings 40 in flap 19 and 41 in flap 20. Stud 30 projects through openings 43 in flap 19 and 44 in flap 18, and stud 31 projects through openings 46 in flap 17 and 48 in flap 18.

In this manner each of the studs 28, 29, 30 and 31 projects through aligned apertures in adjacent flaps so that when subjected to the upward force provided by handle 26, the aligned apertures on each stud and their flaps will tend to separate, but are prevented from doing so by the studs themselves, and in this manner a very rigid handle assembly is provided and no relative movement is permitted between the handle assembly and the carton or its flaps.

The top plate 25 provides the support for the handle 26 and also locks the bottom plate 24 in position. Toward this end, the top plate 25 is generally rectangular in configuration and has apertures 50, 51, 52 and 53 aligned with the studs 31, 28, 29 and 30 for freely receiving the same. For the purpose of locking the top plate 25 to the top of the flaps 18, 20 and sandwiching the flaps between the plates 24 and 25, wing nuts 56 are

provided that may be easily threaded to and removed from the studs.

To assemble the handle assembly 12 to the box, the following procedure is preferably used. With the carton flaps closed, the bottom plate 24 is turned upside down and laid against the upper flaps 18 and 20. The position of the studs on the flaps 18 and 20 is marked with a pencil and punches are made through the flaps 18 and 20 making sure that the punch holes go all the way through the flaps 18 and 20 as well as through the flaps 17 and 19 thereby providing the necessary aligned holes in the adjacent flaps. Thereafter, the bottom plate 24 is positioned within the container with the flaps open. This is accomplished either by supporting the plate 24 on the article within the container or cutting out a piece of cardboard 60 slightly larger in size than the inside of the container 10 so that it can be snugly placed therein in the position shown in FIG. 3 to support the bottom plate 24 during assembly of the handle.

With the bottom plate 24 supported within the container, the flaps 17 and 19 are closed over their respective studs and the studs are permitted to project therethrough. Thereafter, the flaps 18 and 20 are closed over the same studs. The top plate 25 is then placed over the studs with the studs projecting therethrough and the wing nuts 56 threaded to the studs firmly attaching the top plate in position and clamping the flaps between the plates 24 and 25. The carrying handle is then ready for use, and may be removed simply by removing the wing nuts 56 and disassembling the handle in the reverse order described above for assembly.

I claim:

1. A carrying handle assembly for a carton of the rectangular type having four 90° angularly related top flaps, comprising: a base member positionable beneath all of said flaps when in closed positions, a top member positionable on top of all of said flaps when in closed positions, at least two fasteners extending from one of said members to the other of said members, each of said fasteners being positioned so that it projects through two of said flaps to secure the members to all of said flaps, and carrying handle means fixed to the top member.

2. The carrying handle assembly of claim 1, wherein said base member is a generally rectangular plate, said fasteners being threaded fasteners extending upwardly from and fixed to said base plate.

3. The carrying handle assembly of claim 2, wherein said top member is a generally rectangular plate, apertures in said top plate for receiving the threaded fasteners, and wing nuts on top of said top plate and threadedly engaging said threaded fasteners.

4. The carrying handle assembly of claim 1, wherein said fasteners include four threaded fasteners fixed to and projecting upwardly therefrom, said threaded fasteners being spaced approximately 90° from one another so that each projects upwardly through two flaps of the carton.

5. A carrying handle assembly for a carton of the rectangular type having four 90° angularly related top flaps, comprising: a generally rectangular base plate 10 positionable below all of said flaps approximately centrally thereof when the flaps are in the closed position, four threaded fasteners fixed to and projecting upwardly from the base plate, said threaded fasteners being spaced approximately 90° apart so that each fastener extends through two flaps of the carton, a generally rectangular top plate positionable on top of all of said carton flaps when in a closed position, said top plate having four apertures therein for receiving the upwardly projecting threaded fasteners, nut means on each of said threaded fasteners for clamping the plates against the carton flaps, and a carrying handle fixed to the top plate.

6. The carrying handle assembly of claim 5, including means for holding said bottom plate in position beneath the flaps while the flaps are closed over the upwardly projecting fasteners.

7. The carrying handle assembly of claim 6, wherein said means for holding the bottom plate in position includes a rectangular cardboard piece sized to fit snugly within the container interior adjacent the upper portion thereof.

8. A method for attaching a carrying handle assembly to a carton having four 90° related flaps at the top thereof, including the steps of: holding a base plate having at least two fasteners projecting upwardly therefrom within the container at the upper portion thereof, closing two opposed flaps over the fasteners so that each has one fastener projecting therethrough, closing the second opposed flaps over the fasteners so that each has one fastener projecting therethrough, placing a cover plate having a carrying handle over the projecting fasteners and fixing the upper plate thereto.

9. A method for attaching a carrying handle assembly to a carton having four 90° related flaps at the top thereof as defined in claim 8, wherein the lower plate has four spaced fasteners projecting upwardly therefrom, said first set of flaps being closed over the fasteners so that two fasteners project through each flap, the second set of flaps being closed over the fasteners so that two fasteners project through each flap.
